UNITED STATES PATENT OFFICE.

WALTER W. WELPLEY, OF DETROIT, MICHIGAN, ASSIGNOR OF ONE-HALF TO WILLIAM T. McNAMARA, OF DETROIT, MICHIGAN.

TOOTHBRUSH HOLDER.

Application filed December 19, 1919, Serial No. 346,077. Renewed February 16, 1922. Serial No. 537,123.

To all whom it may concern:

Be it known that I, WALTER W. WELPLEY, a citizen of the United States of America, residing at Detroit, in the county of Wayne 5 and State of Michigan, have invented certain new and useful Improvements in Toothbrush Holders, of which the following is a specification, reference being had therein to the accompanying drawings.

10 The object of my invention is to provide a simple, durable, inexpensive, neat and sanitary tooth brush holder in which a tooth brush or similar article may be easily and quickly placed and frictionally held, without any danger of the tooth brush or article 15 becoming accidentally displaced. That portion of the tooth brush or article within the holder is protected from dust and other foreign matter, and the manner in which the 20 tooth brush is held permits of various sizes of brushes being retained within the holder without the bristles being injured or any part of the tooth brush marred. The holder consists of four parts one of which serves 25 two purposes, namely a hanger for the holder and a gripping device for the brush, and it is the simplicity of construction which contributes to a practical device.

The tooth brush holder will be hereinafter 30 considered and then claimed, and reference will now be had to the drawing, wherein—

Figure 1 is a vertical sectional view of the tooth brush holding device, showing a brush therein;

35 Fig. 2 is a front elevation of the device, without the brush, and

Fig. 3 is a horizontal sectional view of the device.

The holder comprises an oblong stall or 40 thimle shaped container 1 having a closed or dome shaped upper end 2 and a lower open end 3, which permits of the bristle end 4 of the tooth brush 5 being placed therein. The stall 1 is preferably made of a trans-

45 parent material, as glass, celluloid or light composition, and the upper closed end 2 thereof has a small vent so that air may circulate through the stall 1 and prevent the accumulation of moisture on the inner wall 50 of the stall which might cause dust and other matter to settle thereof and render the stall unsanitary.

Embracing the outer walls of the stall 1, preferably at the upper and lower ends 55 thereof, are bands 6 having ends thereof ex-

tending through slots or slits 7 in a hanger 8 which has its upper end apertured, as at 9, so that it may be suspended from a hook 10 or attached to a suitable support by suitable fastening means. The lower end of the 60 hanger is bent to provide a hook-shaped resilient clamping member 11 which extends into the stall 1 and frictionally engages the back of the tooth brush 5 to frictionally hold the bristles thereof against the inner front 65 wall of the stall 1.

The bands 6 may be made of celluloid or any material that may be bent or formed to frictionally embrace the stall 1 and the ends of each band are somewhat hook shaped, as 70 at 12 so that the hookshaped ends may be threaded in the slits or slots 7 to bind against the hanger 8 and thus hold the stall 1 relative to said hanger. The hook shaped ends 12 may support the hanger 8 somewhat in 75 spaced relation to a wall or these hook shaped ends may be flattened against the rear wall of the hanger 8, so that the hanger may be tacked or otherwise permanently fixed on 80 the support.

The hanger 8 can be made of celluloid or any material which will provide a resilient clamping end within the stall 1 and when the stall is devoid of a brush the resilient 85 clamping end 11 extends in proximity to the front wall of the stall so as to be in the path of the brush inserted therein. The clamping member 11 recedes as the upper end of the brush is pressed into the stall 1 and the clamping member eventually binds against 90 the back of the brush and positively retains the same within the stall. The width of the hanger 8 permits of the band ends 12 being positively anchored in engagement therewith and the clamping member at the lower 95 end of the hanger is of such width that it will present a sufficient contact area against the back of the brush to frictionally hold the same.

The hanger and bands may be made of 100 white celluloid, in imitation of ivory, so that the holder will present a neat and attractive appearance, and while in the drawing there is illustrated a preferred embodiment of my invention, it is to be understood that the 105 structural elements are susceptible to such changes as fall within the scope of the appended claim.

What I claim is:—

A tooth brush holder comprising a stall 110

having an upper closed end and a lower open end adapted to receive the end of a tooth brush, a hanger supporting said stall and disposed in parallelism therewith, said 5 hanger having its lower end bent to provide a resilient clamping member extending into the open end of said stall, and adapted to be placed under tension by the end of a tooth

brush interposed between said clamping member and the front wall of said stall. ¹⁰

In testimony whereof I affix my signature in the presence of two witnesses.

WALTER W. WELPLEY.
